F. E. ARNDT.
BURIAL VAULT,
APPLICATION FILED MAY 5, 1915.

1,144,579.

Patented June 29, 1915.

UNITED STATES PATENT OFFICE.

FRANKLIN E. ARNDT, OF GALION, OHIO, ASSIGNOR TO DAVID C. BOYD, OF GALION, OHIO.

BURIAL-VAULT.

1,144,579.

Specification of Letters Patent. Patented June 29, 1915.

Application filed May 5, 1915. Serial No. 26,004.

To all whom it may concern:

Be it known that I, FRANKLIN E. ARNDT, a citizen of the United States, residing at Galion, in the county of Crawford and State of Ohio; have invented certain new and useful Improvements in Burial-Vaults, (Case A,) of which the following is a specification.

This invention comprehends certain new and useful improvements in burial vaults, and relates particularly to doors or closures therefor.

The invention has for its primary object a very simple, durable and efficient construction of vault door or closure of the type designed to effectually prevent surreptitious or unauthorized access to the vault, the door locking devices being operable from the exterior of the door or closure, and means being provided whereby when the door is once locked it cannot be subsequently opened.

A further object of the invention is to provide a device of this character in which, in the operation of locking the door, the locking members are first moved outwardly toward and beyond the margin of the door and into engagement with an internal flange which extends around the body portion of the vault, and subsequently, by the application of the sealing cap, a rocking movement or leverage action is imparted to the locking members whereby the closure is compressed tightly against said flange or a gasket or the like interposed between the same and the door.

A still further object of the invention is to provide a device of this character wherein the parts may be very cheaply manufactured and easily assembled, the parts being so few and of such simple construction, that material economies in manufacture are effected, and the vault capable of being sold at a relatively low price and yet at a large profit. And the invention also aims to generally improve devices of this class so as to render them more useful and commercially desirable.

With these and other objects in view, as will more fully appear as the description proceeds, the invention consists in certain constructions, arrangements and combina-

tions of the parts that I shall hereinafter more fully describe and claim.

For a full understanding of the invention, reference is to be had to the following description and accompanying drawing, in which,

Figure 1 is a sectional view of a burial vault embodying the improvements of this invention, the view being taken from the inside of the door or closure and showing the parts in locked position. Fig. 2 is an enlarged transverse sectional view with the locking members extended, and with the sealing cap just about to be applied. Fig. 3 is a fragmentary sectional view showing how the application of the sealing cap will rock the locking members so as to tightly compress the door against the internal flange with which the body of the vault is provided. Fig. 4 is a face view of the revolute actuating device for the locking members, showing the rib formed thereon in the form of an involute spiral, and Fig. 5 is a transverse sectional view through the actuating devices hereinafter specifically referred to.

Corresponding and like parts are referred to in the following description and designated in all of the views of the accompanying drawing by like reference characters.

Referring to the drawing, the numeral 1 designates the body portion of a burial vault, the same being constructed in any desired shape, size, or design, within the purview of my invention, and 2 designates the door or closure. The body portion 1 of the vault is of the end-opening type, in the present embodiment of the invention, and is provided at its open end with an internal flange 3, as best indicated in Fig. 2. The door 2 is designed to abut against this flange, in closed position, or against a gasket 4 interposed between the same and the door.

Applied to the rear or inner face of the door 2 are any desired number of locking members 5, the same being in the form of frames and of any desired number, there being four of these in the present instance. The locking members 5 include locking fingers 6 of any desired number and bifurcated, as shown, so as to embrace studs or bolts 7 which extend through the door 2,

as clearly illustrated in Fig. 2. These studs or bolts 7 assist in holding the locking members 5 in place and in guiding said members in their movements. Preferably, 5 the outer extremities of the locking members 5, or rather the fingers 6 thereof, are beveled, as at 8, for wedging engagement with the inner face of the marginal flange 3, and preferably the locking members are 10 formed with any desired number of bosses 9 to engage the inner face of the door 2 so as to hold the parts in their proper position.

Each of the locking members 5 is formed 15 at its inner end with a shank 10, and each shank is provided with any desired number of teeth or lugs 11 which engage with a spiral rib or groove 12 formed on the inner face of a revoluble actuating member 13 shown in detail in Fig. 4, and in section in 20 Figs. 2 and 3. The actuating member 13 is provided with a tubular outwardly extending stem 14 which projects outwardly through the door or closure 2 and which is 25 non-circular on its outer face, as best illustrated in Fig. 5. Surrounding the stem 14 is the outwardly extending sleeve 15, which forms an integral part of a disk 16 that is applied to the inner face of the door 2 and 30 which is formed on its periphery with ratchet teeth 17 designed for engagement by a spring pressed pawl 18 pivotally secured to the rear or inner face of the door. The stem 15 is revolubly mounted in an 35 opening formed in the door and is provided on its exterior wall with screw-threads 19 to receive the internal threads that are formed on a sealing cap 20, illustrated in Figs. 2 and 3.

40 Mounted within the hollow stem 14 of the revoluble actuating member 13 for the locking members, is a rod or bolt 21, the same being encircled by a helical spring 22 which bears at one end against a nut 23 and re- 45 acts at its other end against the inner end of said stem. The rod 21 projects inwardly beyond the inner face of the actuating member 13 and has secured to it a cross-head 24 which is cruciform in plan view, as clearly 50 illustrated in Fig. 1. The arms of the cross-head 24 are channeled, as clearly illustrated in Figs. 2 and 3, to receive and accommodate the inner extremities of the shanks 10 of the locking members 5.

55 From the foregoing description in connection with the accompanying drawing, the operation of my improved vault door or closure will be apparent. In the practical use of the device, after the casket has been 60 inserted into the vault, the door 2 is applied to the open end thereof with the locking members 5 in their inner or retracted positions. Then, a wrench or similar tool is applied to the hexagonal or outer extremity

of the hollow stem 14 and the actuating member 13 is turned in such a direction that, through the instrumentality of the involute spiral 12 and its engagement with the teeth or lugs 11 of the shanks 10, the locking members will be moved outwardly in a plane parallel to the plane of the door, whereby the outer extremities 8 of the locking members will pass behind the flange 3 and initially secure the door in its locked or closed position. Subsequently, the sealing cap 20 is applied, and as it is screwed on the threaded sleeve 15 of the locking dial or disk 16, it will finally, as is manifest, abut against the outer end of the stem 14, whereupon a further screwing on, or inward movement of, the sealing cap, will obviously move the stem 14 and the locking member 13 of which it forms a part, inwardly, and the inner ends of the shanks 10 of the locking members 5 will also be moved inwardly whereby the locking members are rocked upon their outer extremities as fulcrums, and the door 2 will be compressed still more firmly against the flange 3 or the interposed gasket 4. In this movement of the locking members 5, the cross-head 24 will naturally yield against the tension of the spring 22, while at the same time such cross-head will prevent any lateral movement of, or strain upon, the locking members, and they will 95 take the oblique positions illustrated clearly in Fig. 3.

Thus it will be seen that there is a compound movement of the locking members; first, a sliding movement in an outward direction parallel to the plane of the door 2, and subsequently a rocking movement in a plane at right angles to the plane of the door. By the engagement of the pawl 18 with the teeth 17 of the locking disk or dial 16, it is evident that after the door has once been locked, it is impossible to open it from the outside.

While the accompanying drawing illustrates what I believe to be the preferred embodiment of my invention, it is to be understood that the invention is not limited thereto, but that various changes may be made in the construction, arrangements and proportions of the parts without departing from the scope of the invention as defined in the appended claims.

What is claimed, is:—

1. A vault door, locking members applied to the rear face thereof, an actuating device, a support carried by the door and in which the actuating device is mounted, the support being revolubly mounted in the door and the actuating device being movable axially independently of the support, said actuating device being operatively connected to the locking members whereby a turning movement of the actuating device will move the lock-

ing members outwardly in a plane substantially parallel to the door, and means for moving said actuating device axially and inward in its support whereby to effect a 5 rocking movement upon the locking members.

2. A vault door, locking members applied to the rear face thereof, an actuating device, a sleeve mounted for rotary movement in the 10 door about a fixed axis, the actuating device being mounted in the sleeve and movable revolvably therewith but capable of an axial movement independently thereof, said actuating device being operatively connected to the locking members whereby a turning 15 movement of the actuating device will move the locking devices outwardly in a plane substantially parallel to the plane of the door, and means for moving the actuating device axially in said sleeve and independently thereof whereby to effect a rocking 20 movement upon the locking members.

3. A vault door, locking members applied to the rear face thereof, an actuating device, 25 a sleeve mounted for revoluble movement about a fixed axis in the door, a locking dial movable with said sleeve, the actuating device being mounted in the sleeve and held to turn therewith but capable of axial movement 30 therein, said actuating device being operatively connected to the locking members whereby a turning movement of the actuating device will move the locking members outwardly in a plane substantially parallel 35 to the door, means for moving the actuating device axially whereby to effect a rocking movement upon the locking members, and means co-acting with the locking dial for holding the locking members against re- 40 traction, as set forth.

4. A vault door, locking members applied to the rear face thereof, an actuating device revolvably mounted in the door and free to slide inwardly therein independently 45 of any rotary movement, said actuating device being operatively connected to the locking members whereby a turning movement of the actuating device will move the locking members outwardly, and means for sliding the actuating device inwardly in an axial direction whereby to effect a rocking 50 movement upon the locking members.

5. In a vault door, the combination with locking members capable of a compound 55 movement, namely, a sliding movement parallel to the face of the door and a rocking movement at right angles to the first named movement, an actuating device mounted in the door and operable from the exterior thereof, and means for closing the 60 outer end of the actuating device and for automatically simultaneously moving the actuating device inwardly, there being an operative connection between the inner ends

of the locking members and the actuating 65 device.

6. A vault door, locking members applied to the rear face thereof and capable of a compound movement, namely, a sliding movement parallel to the face of the door 70 and a rocking movement at right angles to the first named movement, a sleeve revolvably mounted in the door, an actuating device mounted in said sleeve and held to turn therewith but movable inwardly independently 75 of the sleeve, said actuating device projecting outwardly like the sleeve from the outer face of the door, an operative connection between the inner ends of the locking members and said actuating device, and a sealing cap applicable upon the sleeve and adapted to abut against the outer end of the actuating device upon engagement with the sleeve, whereby when the sealing cap is applied to the sleeve, the actuating device will 80 be moved inwardly.

7. A vault door, locking members applied to the rear face thereof and capable of a compound movement, namely, a movement parallel to the face of the door and a rocking movement at right angles to the first named movement, an actuating device provided with a spiral rib with which the inner 90 ends of the locking members movably engage, said actuating device being also provided with a stem projecting outwardly beyond the outer face of the door, a sleeve revolvably mounted in the door and projecting outwardly therefrom but movable longitudinally thereof and normally projecting beyond the outer end thereof, and a sealing cap adapted to be screwed upon the sleeve and to abut against the outer end of said stem, as and for the purpose specified.

8. A vault door, locking members mounted upon the rear face thereof and capable of a compound movement, namely, a sliding movement parallel to the face of the door, and a rocking movement at right angles to the first named movement, a sleeve revolvably mounted in the door and projecting from the outer face thereof, an actuating device mounted in said sleeve, the engaging walls of said sleeve and actuating device being such as to compel the movement of both of these parts in a rotary direction while allowing for a longitudinal movement of the stem relative to the sleeve, the actuating device being formed on its inner face with a spiral rib and the inner ends of the locking members being formed with teeth engaging said rib, and a sealing cap adapted to be screwed upon said sleeve and engage the outer end of the stem, as and for the purpose set forth.

9. A vault door, locking members mounted upon the rear face thereof and capable of a compound movement, namely, a sliding movement parallel to the face of the door

door and a rocking movement at right angles to the first named movement, a sleeve revolubly mounted in the door and projecting from the forward face thereof, an actuating device operatively connected to the locking members whereby a rotary movement of the actuating device will impart to the locking members said first named movement, said actuating device being provided with a stem mounted in said sleeve, the engaging walls of the stem and sleeve being non-circular and the stem normally projecting beyond the end of the sleeve whereby a wrench or the like may be applied thereto, and a sealing cap adapted to be screwed upon the sleeve and to engage the outer end of said stem, as and for the purpose set forth.

10. A vault door, locking members mounted upon the rear face thereof and capable of a compound movement, namely, a sliding movement parallel to the face of the door and a rocking movement at right angles to said first named movement, a sleeve revolubly mounted in the door, an actuating device provided with a hollow stem and mounted in the sleeve, the stem being held to turn with the sleeve but capable of an inward and outward movement independently of the sleeve, the actuating device being formed on its inner face with a spiral groove, and the locking members being formed on their inner ends with teeth engaging said groove, a cross-head formed with channeled bars in which the inner ends of the locking members are received, a rod secured to said cross head and extending through the actuating device into the stem thereof, a spring encircling said rod within the stem and tending to draw the cross-head toward the actuating device, and a sealing cap adapted to be applied to the sleeve and to engage the outwardly projecting end of the stem, for the purpose specified.

45. 11. A vault door, locking members mounted upon the rear face thereof and capable of a compound movement, namely, a sliding movement parallel to the face of the door and a rocking movement at right angles to the first named movement, the locking members being formed with inwardly projecting shanks provided with teeth, an actuating device formed on its rear face with a spiral groove in which said teeth are mounted to work, a sleeve revolubly mounted in the door, a locking dial secured to the inner end of said sleeve and mounted upon the rear face of the door and interposed between the same and the actuating device, said actuating device being formed with a non-circular hollow stem projecting outwardly into and through the sleeve, the sleeve being formed with a correspondingly shaped inner wall engaging the exterior surface of the stem, a

cross-head formed with channeled bars in which the shanks of the locking members are freely mounted, a rod secured to said cross-head and projecting outwardly through the actuating device into the hollow stem, a nut on the outer end of said rod, an expansion spring coiled around said rod and bearing against said nut and the actuating device, the stem of the actuating device being longer than the sleeve and protruding therefrom, the sleeve having its periphery threaded, a sealing cap adapted to screw upon said sleeve and to abut against the outer end of said stem, the locking dial being formed on its periphery with ratchet teeth, and a pawl pivotally mounted upon the rear face of the door and engageable with said teeth, as and for the purpose set forth.

12. A vault door, locking members applied to the rear face thereof, an actuating device provided with a stem projecting outwardly through the door and mounted for revoluble movement therein as well as capable of having a sliding movement in an axial direction, and an operative connection between the locking members and said actuating device, whereby a revoluble movement of the actuating device will move the locking members outwardly in a plane substantially parallel to the plane of the door, and an inward sliding movement of the same actuating device will rock the locking members in a plane substantially at right angles to the plane of the door.

13. A vault door, locking members mounted upon the rear face thereof, an actuating device provided with a stem projecting outwardly through the door, and operable from the outer face of the latter, said stem being mounted for a sliding movement in the door in a direction longitudinally of the stem and held for a rotary movement in the door, a spring-pressed guiding device carried by said actuating device, the locking members being interposed between said actuating device and guiding device, and an operative connection between said locking members and the actuating device whereby a rotary movement of said actuating device will move the locking members outwardly in a plane substantially parallel to the plane of the door and an inward sliding movement of the sleeve in an axial direction will rock said locking members in a plane at right-angles to the plane of the door.

14. A vault door, locking members applied to the rear face thereof, an actuating device provided with a stem projecting outwardly through the door, the stem being mounted for a revoluble movement and capable of a sliding movement at right angles to the plane of the door, a guiding device, a rod secured thereto and extending into the

stem, a spring engaging said rod and actuating device tending to move the guiding device toward the actuating device, the locking members being interposed between the actuating device and the guiding device, and an operative connection between the locking members and the actuating device.

In testimony whereof I affix my signature in presence of two witnesses.

FRANKLIN E. ARNDT.
